CLAIM

The ornamental design for a stethoscope, as shown and described.

DESCRIPTION

FIG. 1 is a top, front, perspective view of the stethoscope thereof;

FIG. 2 is a top, right-side, perspective view of the stethoscope thereof;

FIG. 3 is a top, back, perspective view of the stethoscope thereof;

FIG. 4 is a top, left-side, perspective view of the stethoscope thereof;

FIG. 5 is a back, left-side, perspective view of the stethoscope thereof;

FIG. 6 is a front, left-side, perspective view of the stethoscope thereof; and,

FIG. 7 is a back perspective view of the stethoscope.

1 Claim, 7 Drawing Sheets# US D961,770 S
